INFANT'S SLEEPING GARMENT

Grace W. Van Brunt, Kansas City, Mo., assignor to The Grace Company, Belton, Mo., a corporation of Missouri

Filed Sept. 22, 1958, Ser. No. 52,708

Term of patent 14 years

(Cl. D3—17)

Fig. 1 is a front elevational view of an infant's sleeping garment showing my new design; Fig. 2 is a rear elevational view thereof; and Fig. 3 is a front elevational view thereof in open condition

I claim:

The ornamental design for an infant's sleeping garment, as shown.
